(57) **CLAIM**

The ornamental design for a lamp for manicure, as shown and described.

DESCRIPTION

FIG. 1 is a front, right and top perspective view of a lamp for manicure, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top plan view thereof;

FIG. 8 is an enlarged bottom plan view thereof;

FIG. 9 is a perspective view showing the lamp for manicure in an extended position such as it would appear while being used.

FIG. 10 is another perspective view showing the lamp for manicure in an extended position such as it would appear while being used.

FIG. 11 is an enlarged view of portion of FIG. 1;

FIG. 12 is an enlarged view of portion of FIG. 1; and,

FIG. 13 is an enlarged view of portion of FIG. 2.

The broken lines shown in the drawings illustrate portions of the lamp for manicure that form no part of the claimed design. The dot-dash broken lines shown in FIGS. 1, 2, 11, 12 and 13 depict the bounds of the enlarged views and form no part of the claimed design.
